UNITED STATES PATENT OFFICE

164,160

CONTAINER FOR PERISHABLE FOODS

Calvin Davis, Salinas, Calif.

Application May 26, 1950, Serial No. 10,216

Term of patent 14 years

(Cl. D58—12.6)

To all whom it may concern:

Be it known that I, Calvin Davis, a citizen of the United States, residing at Salinas, Monterey County, State of California, have invented a new, original, and ornamental Design for a Container for Perishable Foods, of which the following is the specification, reference being had to the accompanying drawing, forming a part hereof.

I claim:

The ornamental design for a container for perishable foods, as shown.

CALVIN DAVIS.
